UNITED STATES PATENT OFFICE.

NICHOLAS F. DODSON, OF DENVER, COLORADO.

MAN'S UNDERGARMENT.

Application filed October 29, 1927. Serial No. 229,685.

This invention relates to improvements in undergarments or drawers for men and has reference more particularly to a garment of this type which is buttonless.

5 The object of this invention is to produce an undergarment or drawers that can be easily put on and which will be comfortable to wear and which at the same time shall be so constructed that there will be no buttons to become lost.

10 It is well known that buttons are very difficult to keep in place, since the universal introduction of washing machines and power wringers, as the wringers very frequently remove the buttons, and besides this, it has been found if undergarments are provided with a belt formed in part by sections of elastic material, that they will be more comfortable to wear, as they will 15 yield to the requirements of the body and at the same time fit snugly so as to give a 20 feeling of support and comfort to the wearer.

15 My invention, briefly described, consists in constructing an undergarment with a belt which has two or more sections of elastic material incorporated in it, whereby the belt will yield sufficiently to permit the garment to be applied and removed and at the same 25 time will exert sufficient force to hold the garment in place.

Having thus briefly described my invention, I will now proceed to describe the same in detail, and reference for this purpose will be had to the accompanying drawing in which the preferred embodiment 30 thereof has been illustrated and in which:

35 Fig. 1 shows a perspective view of my improved garment as it will appear when in place on the wearer's body, the latter being indicated by dot and dash lines;

40 Fig. 2 shows a rear view of the garment and illustrates the construction in relation to the elastic inserts;

45 Fig. 3 is a front view of the garment with a small portion broken away to show a reinforcing lining; and

50 Fig. 4 is a section taken on line 4—4, Fig. 2, showing the manner in which the elastic inserts are secured to the belt.

55 In the drawing I have illustrated a pair of drawers having legs of knee length. These legs have been indicated by reference numeral 1 and 2. The upper end of the drawers is provided with a belt, which, in

the embodiment shown, has been formed of four sections which have been numbered respectively 3, 4 and 5, the reference numeral 5 being applied to the two inserts of elastic material which form part of the 60 belt.

65 It will be observed from Fig. 1 that the belt section 3 which is located at the front of the garment is of considerable width and has a downwardly extending triangular portion 6, which covers the greater part of the abdomen. Section 3 terminates at lines 7, where it is connected with one side of the elastic inserts 5 in the manner indicated in Figs. 2 and shown in detail in Fig. 4. The 70 other sides of the elastic inserts are connected by means of a belt section 4 which, in the embodiment illustrated, has been shown somewhat narrower than the width of the elastic inserts, although this feature of the 75 construction is not considered to be material as it is obviously permissible to make the section 4 wider, if desired. The edges of the elastic 5 are inserted between the ends of the belt sections 3 and 4 in the manner 80 shown in Fig. 4, the ends of the belt sections being turned inwardly and the whole stitched together by means of two rows of stitching 8. In the particular design illustrated where the vertical dimension of the elastic 85 is greater than the width of the belt section 4, a suitable notch must be cut out of the material of the drawers so as to provide the necessary space. The material composing 90 the drawers is gathered along the lower edge of the elastics in the manner indicated by reference numeral 9, in Fig. 2, so that when the elastics are extended, the seams and the material of the drawers will not be subject to strains. As these drawers are constructed 95 in such a way that the belt is endless, the ordinary placket slot has been dispensed with and replaced by a placket hole 10. The material around the placket hole has been 100 reenforced by lining 11 in the manner shown in Fig. 3. The specific construction of the drawers is not material, except insofar as this relates to the belt, but mention may be made here of the fact that the specific 105 drawers illustrated is formed from two pieces connected by a seam 12 in the manner indicated in Fig. 2.

110 It is obvious that a drawers constructed in the manner described can be easily put on and taken off as the belt section will yield

sufficiently to permit it to pass over the hips and when it is in place, it will fit the body snugly and give a sense of support without any undue restricting effect, such as noticed 5 when an unyielding belt is employed. A drawers constructed in the manner described, in addition to being more comfortable and more quickly put on and removed, is also free from the aggravating trouble of lost 10 buttons as all buttons and button holes have been dispensed with.

It is obvious that this construction of belt can be applied to other garments than the one illustrated, and I therefore wish to call 15 attention to the fact that the specific embodiment shown is for the purpose of illustration and description only, and that the invention should not be restricted to this garment un-

less such restriction is required by the state of the prior art.

Having described the invention what I claim as new is:

A man's undergarment having an endless belt composed of alternate sections of elastic and nonelastic material, that portion of the belt located in front being wider at the center and tapering towards the ends, the ends of the front section being each secured to one end of two substantially rectangular sections of elastic webbing, and a rectangular belt 25 section connecting the other ends of the web sections, said end forming the back section of the belt.

In testimony whereof I affix my signature.

NICHOLAS F. DODSON.
